P. W. Karpman
ATTORNEY

UNITED STATES PATENT OFFICE.

NATHAN BIEBER, OF POLAND, OHIO.

LOADER FOR CORN BINDERS.

1,426,347.

Specification of Letters Patent. Patented Aug. 22, 1922.

Application filed December 5, 1921. Serial No. 520,127.

To all whom it may concern:

Be it known that NATHAN BIEBER, a citizen of the United States of America, residing at Poland, in the county of Mahoning 5 and State of Ohio, has invented certain new and useful Improvements in Loaders for Corn Binders, of which the following is a specification.

The object of this invention is to provide 10 an elevator and loader for corn binders, the same to be extremely simple and inexpensive in construction.

A further object is to provide a device 15 of this class which may be attached to ordinary corn binders.

A still further object is to provide a device of this class so constructed and arranged as to elevate the corn bundle by means of a single chain conveyor, so as to drop said 20 bundle crosswise upon a wagon to be driven underneath the outer end of said elevator, and to deliver the bundles in transverse layers so that there will be no necessity of manual labor in loading the same upon said 25 wagon.

This invention consists in certain details, in the construction, arrangement and combination of these various parts of the device, whereby the objects contemplated are obtained, as hereinafter more fully set forth, 30 pointed out in the claim, and illustrated in the accompanying drawings, in which:

Figure 1 shows a rear elevation of the elevator, and the wagon receiving the load.

Figure 2 is a top plan view of the device 35 showing a bundle being carried, butt first in the position taken by using a single conveyor chain.

Figure 3 is a detail view showing a section 40 of the chain race and chain.

In the accompanying drawing I have used the reference numeral 1 to indicate the wagon, which is drawn by independent means from that of the loading device.

By referring to Figure 1 it will be seen 45 that I have provided a support member 2 which may be attached to the binder in any suitable manner. Upon this support member 2, I have provided a support arm 3 which supports a platform 4. Positioned 50 upon this platform 4, I have provided a chain race 5. Within this chain race 5 a chain 6 is caused to move by means of a drive shaft 7 which may receive its energy

by any desirable means from the movement 55 of the corn binder.

The drive shaft 7 has mounted upon its rear end in a slidable manner a sprocket wheel 8. The upper end 9 of the chain race 5 is provided with support arms 10 carrying 60 a sprocket 11.

By referring to Figure 2 it will be seen that the platform 4 takes the form of a parallelogram with the outer rear corner of the same cut away from point 12 to point 13, 65 thus giving an edge between the points 12 and 13 at approximately 45 degrees from the chain race 5.

In operation the bundle 17 is thrown out by means of the binder upon the edge 14 of 70 the platform 4, where the prongs 15 of the chain 6 grasp the bundle 17 near the band 16, and carry the same upwardly and outwardly upon the elevated chain race 5 and upon the platform 4. As the chain grasps 75 the bundle 17 near the butt end 18, the butt end 18 is carried more rapidly than the other end 19 of the bundle 17. This movement is due to the elevation of the chain race 5 and the retarding frictional movement of the end 19 upon the platform 4. The bundle 17 as shown in Figure 2 shows approximately the position the bundle 17 will take when nearing the end 9 of the chain race 5. When the bundle is carried to 80 the extreme outer point of the sprocket 11, the bundle 17 falls by means of gravity, and slides along the edge formed between the points 12 and 13 of the platform 4, and upon the platform 4, thereby retarding the movement of the end 19, so that the bundle 17 is delivered upon the wagon as shown in 85 Figure 1, or crosswise upon the wagon. The wagon 1 is driven at such a speed underneath the device so as to distribute the bundle 17 as desired in securing the load. 90

The chain race 5 may be adjusted forward or backward in order to provide for the varying lengths of the corn being elevated.

What I claim is:

In a device of the class described, a platform, said platform being rectangular in form with the exception of having the rear outer corner of the same cut away, thereby forming an angle approximately 45 degrees from the front edge of said platform, a chain race secured to said platform in an 100 105

adjustable manner near the front edge of said platform, a drive shaft provided with a slidably mounted sprocket carrying a chain, a chain passing over said sprocket and functioning in said chain race, a sprocket secured to the outer end of said chain race for the purpose of carrying said chain, a plurality of prongs formed on said chain,

means for supporting said device in conjunction with a corn binder, substantially as described for the purpose set forth.

In testimony whereof I affix my signature.

NATHAN BIEBER.
